METHOD FOR DESALTING AND DEWATERING
CRUDE COAL TARJoseph M. Muller, Portage, Ind., assignor to United States Steel Corporation, a corporation of New Jersey
Filed Mar. 2, 1961, Ser. No. 92,945
7 Claims. (Cl. 208—39)

This invention relates generally to the recovery of crude coal tar from the destructive distillation of bituminous coal, and more particularly to a method for dewatering and desalting, i.e. reducing water and water-soluble salts in the crude coal tar thus produced, prior to tar distillation.

In conventional coke-plant practice, the foul gas from the coke ovens is cooled by spraying with flushing liquor which, along with the condensable tars and other compounds, flows to a decanter for separation of the liquor from the condensed tar. The flushing liquor is recycled for further gas cooling while the condensed tar is pumped to a wet-tar storage tank. The gas and remaining vapors are further cooled in primary coolers, the condensate comprising tar and liquor being decanted and separated. The tar is pumped to a wet-tar storage tank. Primary-cooler tar is less viscous than flushing-liquor tar. These tars may be combined or separately stored for different end uses. In the practice under consideration they are combined in a wet-tar storage tank for subsequent distillation.

Production of crude coal tar as hereinabove described is effected by condensation of a vapor to a liquid. The condensation results in entrainment of liquor with the tar which does not separate completely in the described decantations, resulting in so-called wet tar. The liquor contains a number of dissolved salts, and by desalting is meant a reduction in these water-soluble salts. Ammonium chloride is one of these salts and is important since in subsequent tar distillation, it is deleterious to steel equipment, especially at the higher temperatures attained in distillation equipment. The desalting operation to be described and claimed involves the dilution of and reduction in ammonium chloride principally, although it is to be understood that there will be a reduction in the other soluble salts present in the wet-tar liquor.

In conventional practice the entrained liquor is separated by further decantation with or without heating, or by the use of a centrifuge. While these means serve to reduce the entrained liquor or moisture content they do not reduce the salt content of the residual liquor.

I have discovered that numerous advantages over conventional practice are obtained by admixing with wet tar, water at a temperature higher than that of the tar, heating the admixture to at least about 100° C. and allowing the heated admixture to separate into liquor and dewatered-tar layers in a substantially full, bottom-heated storage tank with gradual reduction in temperature from top to bottom of the tank. Chemical additions may further reduce the ammonium-chloride content of the dewatered tar.

A complete understanding of the invention may be obtained from the following detailed description and explanation which refer to the accompanying drawing illustrating the present preferred practice. The single figure of the drawing is a diagrammatic representation of a system for carrying out the method of my invention.

Referring now in detail to the drawing, wet coal tar is introduced by a pipe 10 from decanters (not shown) to a wet-tar storage tank 12. The entrained-liquor or moisture content of the tar may vary widely, but is usually about 5% to 12% by volume of the tar. The ammonium-chloride content of the wet tar may vary widely

2

but is usually about .010% to .030% by weight of the wet tar. Steam-heating coil 14 serves to maintain the effluent-tar temperature between about 75° C. and 95° C. Tar issuing from the bottom of tank 12 is pumped by pump 16 and pipe 18 to a heat exchanger 20. Water at a temperature preferably hotter than the tar, usually at a temperature between about 80° C. and 97° C., is injected through pipe 22 into the tar-traversing pipe 18. Control valve 24 supplies sufficient water to raise the total liquor or moisture content of the tar to between about 10% and 15% by volume of the tar, thereby diluting the salt contained in the liquor.

The admixture flowing through heat exchanger 20 is heated by steam from pipe 26 to at least about 100° C., preferably to between about 102° C. and 110° C., thereby reducing the viscosity of the tar content of said admixture. A thermocouple in pipe 28 actuates a temperature controller 30 which in turn controls steam flow by means of valve 32. The heated admixture in pipe 28 flows to the top of a dewatered-tar storage tank 34. Contrary to conventional practice of maintaining the tar hotter in the bottom of the tank than at the top, the tar in tank 34 is at least equal in temperature to but preferably hotter at the top, because of said heated admixture flowing thereto, whereas the bottom-tar temperature is maintained between about 95° C. and 98° C. by steam coil 36. Operating in this fashion to maintain a hotter, lower-viscosity tar in the upper portion of the tar layer, it has been found that the entrained liquor separates more efficiently, despite the deliberate increase in the liquor or moisture content.

The combined liquor layer 38 and dewatered-tar layer 40 substantially fill tank 34 at all times. Float 42 acting through transmitter 44 and cable 46, operates valve 48 to control wet-tar input substantially equal to dewatered-tar flow to the stills. Liquor flows from tank 34 through valve 50 which may be left open, but preferably is manually operated periodically to maintain a liquor layer between about 3 inches and 12 inches in a conventional 500,000-gallon tar-storage tank. Transmitter 44 is manually adjusted to raise the tank level and to overflow liquor through valve 50.

Dewatered tar, its liquor content reduced to below about 3% and its ammonium-chloride content to below about .006% by weight of the tar, flows from the bottom of tank 34 through pipe 52 and pump 54 to a tar still (not shown). A water solution of sodium carbonate may be used to react with the ammonium chloride to form the more stable sodium chloride. The solution in tank 56 flows through pipe 58 pump 60 and pipe 62 to pipe 52. Admixture ahead of the pump provides sufficient turbulence for effective reaction with the ammonium chloride.

It will be apparent that the tar tanks, pumps, controllers and heat exchanger may be of any design known to effect the desired result. In particular, heat exchanger 20 is of the tube type, the tar flowing through the tubes.

A specific example of the practice of the invention, giving quantities involved, is set forth below.

In a typical coke plant producing about 150,000 gallons per day of combined flushing-liquor and primary-cooler tars, the tars from the decanters are stored in one or more large, e.g., 500,000-gallon wet-tar storage tanks 12. Coil 14 maintains the tar between about 75° C. and 80° C. The tar containing about 8% by volume of entrained liquor and having an ammonium-chloride content of about .015% by weight of wet tar is admixed with water between about 80° C. and 90° C. in a quantity sufficient to raise the liquor content to about 15%. The admixture is thereafter heated in heat exchanger 20 to between about 102° C. and 110° C. and conducted to dewatered-tar

storage tank 34 of 500,000-gallon capacity, the combined liquor and dewatered-tar volume being about 465,000 gallons. The liquor layer, about 3% of the total depth, is controlled between about 3 inches and 9 inches, liquor being removed from the tank 34 at 8 hour intervals by raising the tank level through manual operation of transmitter 44. Coil 36 maintains the tar temperature in the bottom of the tank between about 95° C. and 98° C. Dewatered tar flowing from the bottom of tank 34 has a liquor content of about 2.5%, and an ammonium-chloride content of about .005%, a reduction of about 67% of the ammonium-chloride content of the tar in tank 12. Reaction of the ammonium chloride to form sodium chloride is effected with a 12% water solution of sodium carbonate, an excess of about 60% over theoretical for the reaction being found to produce the desired results.

While the above example illustrates a preferred method of operation, other conditions of operation may be used without departing from the spirit of the invention. The wet-coal tar with its entrained liquor will vary in temperature between about 75° C. and 95° C. according to the season and the liquor content. The temperature will normally be maintained higher in colder weather and as the liquor content increases, to aid in separation of the liquor. It is preferable for good mixing to add water at a temperature higher than that of the tar, the water temperature being at least about 2° C. hotter than the tar. Water admixture to a total of about 10% to 15% liquor is a good practical limit where an ammonium-chloride removal problem exists. The total liquor content may be increased to about 18%, but it should be appreciated that, with further increase in the liquor content, the retention time in the dewatered-tar storage tank must be increased for good liquor separation. Additional liquor will flash-off too much steam in this tank. At below about 10% total liquor, less reduction of ammonium chloride will take place than is possible with my method. It has been found that the viscosity of a mixture of flushing-liquor and primary-cooler tars heated to between about 100° C. and 110° C. will be reduced sufficiently to permit efficient separation of liquor with bottom heating to between about 95° C. and 98° C. Within the practical limits of 100° C. and 110° C. to which the admixture to the dewatered-tar tank is heated, a higher viscosity flushing-liquor tar, when treated alone, should be heated to the high side of this range, and a lower-viscosity primary-cooler tar to the low side of the range. Under the above temperature conditions and operating with a substantially full tank and substantial balance between input and output of the dewatered-tar tank, sufficient retention time is afforded the admixture for separation of liquor and tar. It is obvious from the principle of this invention that a longer retention time, if required, may be achieved with a larger tank or a reduced throughput. As for maintenance of the 3" to 12" liquor layer, it is preferred to operate on the low side of the range. At above 12", the incoming admixture may carry down too much liquor.

The invention is characterized by several distinct advantages. In the first place, the separation of liquor and tar is a relatively simple, inexpensive and efficient process as compared to the former practice of centrifuge separation of liquor and tar which involves additional maintenance expense. Wet tar with a liquor content of 5% to 12% and higher can be reduced consistently to between about 2.0% and 3.5% liquor content.

Secondly, the addition to the wet tar of water at a temperature higher than that of the tar dilutes the ammonium-chloride concentration of the wet tar. Hence, each unit of liquor remaining in the tar contains less ammonium chloride than the same unit of liquor in the wet tar. With the efficient liquor reduction the overall ammonium-chloride content is consistently reduced up to 70%. Hence, the tar may be distilled with a greatly reduced deleterious effect on the distillation equipment.

Thirdly, the process can be easily varied to handle the higher-viscosity flushing-liquor tar and the lower-viscosity

primary-cooler tar. Utilizing the principle of this invention, tars with viscosities outside these limits may be processed.

Fourthly, residual ammonium chloride may be reacted with sodium carbonate to form sodium chloride. The economics thereof is improved because of the reduction in ammonium-chloride content. This reaction converts unstable ammonium chloride to stable sodium chloride, which is eliminated with the pitch.

10 Fifthly, an operator may be faced with a sudden and even prolonged period of excessively high liquor content in his wet-tar storage tank. In such an emergency he may reduce or even eliminate his hot-water addition, effect high liquor separation in the dewatered-tar storage tank 15 with increased retention time and neutralize the additional ammonium chloride by increasing the sodium-carbonate addition.

Finally, an operator may not have a chloride problem when using my process with the hot-water addition. For 20 example, the end use may not require reduction of the chlorides, or the chloride content may be sufficiently low that further reduction through hot-water addition is unnecessary. Under these conditions, without hot-water addition, the wet tar may be heated to between about 100° 25 C. and 110° C. and separated from liquor in a substantially full, dewatered-tar storage tank.

Although I have disclosed herein the preferred practice of my invention, I intend to cover as well any change or modification therein which may be made without departing from the spirit and scope of the invention.

I claim:

1. A method of desalting and dewatering wet coal tar comprising admixing therewith water at a temperature higher than that of the tar, raising the temperature of 35 the admixture to between about 100° and 110° C., conducting the heated admixture to the top of a storage tank, maintaining a descending temperature gradient in said admixture from the top of said tank to the bottom of at least about 5° C. while allowing the admixture to separate, 40 conducting separated liquor from the top of said tank and cooler dewatered tar of reduced water-soluble salt content from the bottom of said tank.

2. A method as defined in claim 1 characterized by admixing with wet coal tar, water that is at least about 2° C. hotter than the wet coal tar.

45 3. A method as defined in claim 1 characterized by admixing with wet coal tar, sufficient water to raise the total liquor content thereof to between about 10% and 15% by volume of liquor.

4. A method as defined in claim 1 characterized by 50 maintaining the dewatered-tar temperature in the lower portion of said storage tank at between about 95° C. and 98° C.

5. A method as defined in claim 1 characterized by maintaining said tank substantially full of tar and liquor, 55 substantially balancing dewatered tar withdrawal and admixture admission to said tank and allowing liquor to accumulate in a layer to a maximum depth of about 12 inches.

6. A method of dewatering wet coal tar containing at 60 least about 10% moisture comprising raising the temperature of said tar to between about 100° and 110° C., conducting heated tar to the top of a storage tank, maintaining a descending temperature gradient in said admixture from the top of said tank to the bottom of at least about 5° C. while allowing tar and liquor to separate, 65 maintaining said tank substantially full of tar and liquor, conducting separated liquor from the top of said tank, maintaining dewatered tar at a temperature between about 95° C. and 98° C. at the bottom of said tank and withdrawing it therefrom.

7. A method of desalting and dewatering wet coal tar comprising admixing with coal tar at a temperature between about 75° C. and 95° C., containing between about 5% and 12% entrained liquor by volume, said liquor containing between about 0.010% and .030% ammonium

chloride by weight of said tar, sufficient water to produce an admixture containing about 15% liquor by volume, said water being at a temperature not exceeding 97° C., raising the temperature of the admixture to between about 102° C. and 110° C., conducting said heated admixture to the top of a storage tank, maintaining a descending temperature gradient in said admixture from the top of said tank to the bottom while allowing tar and liquor to separate, maintaining said tank substantially full of tar and liquor, drawing off dewatered tar from the bottom of the tank in substantially the volume of admixture admitted, maintaining said tar at a temperature between about 95° C. and 98° C., whereby it has an ammonium-

chloride content of no more than about .006% by weight of tar, a liquor content of less than about 3%, and drawing off liquor periodically from the top of said tank.
